Jonathan Payne Russellville Kentucky
Letters Patent

The schedule referred to in these letters patent and making part of the same containing a description in the words of the said Jonathan Payne himself of his improvement in the Lever Prop.

To all to whom these presents shall come,

Be it known that I Jonathan Payne of Russellville in the county of Logan, and State of Kentucky, have invented a new and useful Lever Prop and that the following is a full and exact description thereof together with a complete drawing hereto subjoined and referred to marked 3-3 the different parts and structure of which is specifically set forth as follows, to wit: The bottom sill marked A, A, to be made of solid timber squared 24 by 20 inches measuring in length from 30 to 50 feet as the greater of leg power desired may require B, representing 2 upright ^{center} pieces hewn of solid timber 10 feet long 18 inches wide and six inches thick dovetailed one of each side of sill A, A, precisely in the centre of said sill and bolted with a strong iron pin through through said upright pieces being placed in said sill so as to preserve the space of 12 inches between them from top to bottom. Between said near the top of said upright pieces marked B, and appt. is suspended the main beam marked C on the drawing by an iron pin 3 inches in diameter and twenty four inches long passed through 8 pieces D, and beam C, beam C from 30 to 50 feet in length and squared 18 by 12 inches. Letters D, representing 3 upright pieces placed at the distance of 14 feet from each end of sill A, A, of same width and thickness of pieces B, from 12 to 18 feet long and dovetailed into sill A, A, at each end as open as said upright pieces D.

9085 X

designed to keep within its proper sphere of action lever C, the cog wheels C, in the drawing especially the large wheel measuring 18 feet in diameter in the proportion to the scale of proportion given in the foregoing parts, and the cast iron wheel and nut F, from 7 to 8 inches in diameter are hung upon an iron axle of two inches square fixed on two upright pieces of the same width as upright pieces B. & D, and 4 inches thick dovetailed into sills A. & B, one foot from each end of A. & B. sill rising above said sills 16 inches and marked on the drawing H, said axle to be "placed" on said upright pieces H, as then the wheel or nut F, shall run between said pieces H, and the large wheel C, on the outside of them the small cast iron wheel or nut with a crank marked on the drawing C, are placed on iron axles inserted through upright pieces D, which wheel or nut is to be inserted or placed so as to fit with its cog exactly into those of the wheel C, middle lever H, are to be used for pressing flowers, manufacturing Tobacco, and all descriptions of oil, these lever bars are fastened by a pin into and between upright pieces D, at a convenient height from sills A. & B, and operated on by lever C, by means of an iron suspender made of two iron bars hinged one on each side of lever C and marked down the drawing, the suspender G, are cast iron rods with cog fit into the cog of wheels or nut H, fastened by iron pins in the ends of lever C, and passing when drawn down at their lower end, through sills A. & B, lever C, is altogether sufficient for pressing large heads of Tobacco or baling cotton and this uses will dispense with the use of the upper lever H, This machine is designed to be used in pressing tobacco, baling cotton and pressing oil made of all kinds of beans or seeds, as well as packing flowers, pressing seeds and making manufactured chewing Tobacco.
